UNITED STATES PATENT OFFICE.

THOMAS BURNARD, OF CUYAHOGA FALLS, OHIO, ASSIGNOR OF ONE-FOURTH TO
HENRIETTA HELLERS, OF CUYAHOGA FALLS, OHIO.

DEVICE TO STOP FISH FROM DITCHES.

1,180,564.

Specification of Letters Patent. Patented Apr. 25, 1916.

Application filed November 6, 1913, Serial No. 799,577. Renewed October 15, 1915. Serial No. 56,143.

To all whom it may concern:

Be it known that I, THOMAS BURNARD, a citizen of the United States, residing at Cuyahoga Falls, in the county of Summit 5 and State of Ohio, have invented certain new and useful Improvements in Devices to Stop Fish from Ditches, of which the following is a specification.

This invention relates to devices to prevent fish from entering irrigating ditches or the like, the principal object of this invention being to provide an effectual barrier through the medium of a revoluble element or water wheel with which is associated audible means for producing a constant clicking sound so as to intimidate fish, or like animate beings coming adjacent the water wheel, causing them to be driven therefrom.

20 A further object of the invention is to further insure the prevention of the fish entering the irrigating ditches by providing suitable brush elements so arranged as to contact with the revoluble element or water wheel during its rotation, and incidentally cleansing the element of adhering debris which has heretofore been instrumental in retarding the operation of the water wheel.

Other objects as well as the nature, characteristic features and scope of my invention will be more readily understood from the following description taken in connection with the accompanying drawings and pointed out in the claims forming a part of 35 this specification.

Referring to the drawings:—Figure 1 is a front elevation of the device constructed in accordance with my invention; Fig. 2 is a vertical sectional view of the same; Fig. 3 is a side elevation of the brush elements; Fig. 4 is a longitudinal sectional view of my improved means for producing an audible report; and Fig. 5 is a top plan view of my improved rod securing staple.

45 In the drawings wherein is illustrated the preferred embodiment of this invention, in order to illustrate the application thereof a flume or sluice-way 5 is provided in which are arranged parallel walls 6 which are made of concrete or any other suitable material, and are arranged a predetermined distance apart so as to allow for the passing of water therebetween and at the same time providing ample space in which to allow

for the free rotation of the water wheel. 55 Mounted between the parallel walls 6 is a frame 7 which is preferably made of metal and is in engagement with the bottom of the flume and the inner faces of the concrete walls 6 through the medium of arms 8 or the like as shown to advantage in Fig. 1, the frame 7 having a circular portion 9 thereof cut-out which is of a diameter slightly larger than the diameter of my improved revoluble element or water wheel 10. 65

Extending transversely of the flume or sluice-way 5 is a supporting element or bar 11 which has the opposite ends thereof engaged in the opposite walls 6 and is provided with a central opening through which 70 is engaged an axle or shaft 12, said axle having fixedly secured thereon an operating wheel 13 which extends exterior of the supporting element 11.

Fixedly carried by the shaft or axle 12 is 75 my improved water wheel 10 which in the present instance comprises a hub 14, spokes 15 and a felly 16, said spokes radiating from said hub and having engagement with the side of the felly, instead of the inner periphery thereof, through the medium of U-shaped staples 16' as advantageously illustrated in Fig. 5. Secured to the outer periphery of the water wheel 10 is a tire or annular collar 17 one end of which lies in a 85 plane with one side of the felly 16 while the opposite edge thereof extends beyond the plane of the wheel as advantageously illustrated in Fig. 2. The axle is supported on one side by the supporting bar 11 heretofore described and on the opposite side by a similar supporting bar 18, said bar 11 having arranged on the inner face thereof a plurality of brush elements 19 each of which comprises a head having bristles, preferably made of wire, extending therefrom, the free ends of said bristles adapted for engagement with the spokes 15 of the wheel 10 during the rotation of the same. The 90

brushes as is obvious will not only facilitate the prevention of fish or other animate beings from coming through the wheel, but will likewise cleanse the wheel of adhering debris as previously pointed out.

Mounted on the front face of the wheel 10 and having engagement with the felly is a plate 20 which has extending therefrom a plurality of cleaning fingers 21 which are

adapted for engagement with the bristles of the brush elements 19 thereby freeing the latter from foreign substances which gather therein, said plate being secured to said wheel through the medium of nuts and bolts 22 or other analogous detachable fastening means. Arranged at an inclination and in uniformly spaced apart relation on the inner periphery of said felly 16 are cylinders 23 which are preferably of a cylindrical contour and are provided on the opposite ends thereof with external screw-threads which are detachably engaged with caps 24, whereby to provide a receptacle in which is 5 removably mounted a plurality of weighted balls 25 which are adapted to be simultaneously actuated in said cylinder or receptacle with the actuation of said wheel thereby emitting an audible report so as to 10 intimidate fish or the like in the waters adjacent the water wheel, causing the same to be retarded in their course.

The wheel 10 will be rotated to a certain extent through the medium of the flow of the stream in which it is mounted, but in 25 order to cause the rotation of the same at all times, I have provided a suitable power element 26 with which is engaged a belting 27, the belting having engagement with the operating wheel 13 so as to actuate said wheel 10 when the power element is operated.

It will be understood that the above description and accompanying drawings comprehend only the general and preferred embodiment of my invention and that various minor changes in details of construction, proportion and arrangement of the parts 35 may be made within the scope of the ap-

pended claims and without sacrificing any of the advantages of my invention.

Having thus fully described my invention what I claim as new and desire to secure by Letters Patent is:—

1. In a fish screen, the combination of a sluice way, a fish barrier rotatably mounted in the sluice way, a plurality of cleaning elements mounted in said way and adapted to contact with said barrier to prevent the accumulation of debris thereon, and means carried by said barrier to cleanse said cleaning elements.

2. A fish screen including a revolving wheel, brush elements arranged in proximity to said wheel and having engagement therewith, and means carried by the wheel for cleaning said brushes.

3. A fish screen including a revolving wheel, brushes arranged in proximity to said wheel and having engagement therewith, and cleaning fingers carried by said wheel and actuatable therewith for freeing said brushes of adherent materials.

4. A fish screen including a revolving wheel, brush elements rigidly carried adjacent said wheel and having engagement therewith, cleaning fingers carried by said wheel adapted for engagement with said brush elements during the rotation of said wheel for cleansing said brushes of adherent materials, and means arranged in proximity to said wheel for revolving the same.

In testimony whereof I affix my signature in presence of two witnesses.

THOMAS BURNARD.
